UNITED STATES PATENT OFFICE.

GEORGE F. MAIDENS, OF COLUMBUS, OHIO.

PUSH CRUMB-TRAY.

1,132,951.

Specification of Letters Patent. Patented Mar. 23, 1915.

Application filed March 2, 1914. Serial No. 821,974.

To all whom it may concern:

Be it known that I, GEORGE F. MAIDENS, a citizen of the United States of America, residing at Columbus, in the county of 5 Franklin and State of Ohio, have invented certain new and useful Improvements in Push Crumb-Trays, of which the following is a specification.

The present invention relates to improvements in crumb trays, particularly designed to clear the crumbs from a table cover after a meal, but it will of course be understood that the device may be used for similar purposes in other circumstances.

15 The primary object of the invention is the provision of a simple but effective device by means of which the crumbs and other particles of food may be quickly cleared, as by a scoop, from the table cover after a 20 meal, the result being effected with one hand only. The device is comparatively inexpensive in cost, simple in construction, and is not likely to become deranged or inoperative from frequent use.

25 The invention consists essentially in the combination with the tray or receptacle of a freely rotatable and yieldingly supported member operating in front of the advancing tray, and in certain novel features of construction and combinations and arrangements of parts as hereinafter set forth and claimed.

In the accompanying drawings I have 35 illustrated one complete example, and a modification thereof, showing the best modes I have so far devised for the practical application of the principles of the invention.

Figure 1 is a plan view of a tray according to my invention. Fig. 2 is a vertical 40 sectional view. Fig. 3 is a view similar to Fig. 2, but with the rotatable member omitted. Fig. 4 shows the tray in section with an accumulation of crumbs therein and the rotatable member in position to prevent exit or spilling of the crumbs from the tray. Fig. 5 shows in section a modified 45 form of yieldable support for the rotatable member or roller. Fig. 6 is a plan view of a portion of the tray showing the yielding support of Fig. 5.

In the preferred embodiment of my invention as shown in Figs. 1 to 4 inclusive the tray is of usual or accepted type with the bottom 1, walls 2 and handle 3, but the 55 front ends 4 of the side walls 2 provide extensions which project beyond the front

beveled scraping edge 5 of the tray bottom, as clearly seen in the drawings and especially Fig. 3. These extensions are each fashioned with a vertically extending slot 6 and an outwardly turned flange 7 which forms a "runner" to pass smoothly over the surface to be "crumbed." The vertically extending slots are designed to provide 60 bearings for the pins or pintles 8 which project from the ends of the rotatable member or roller 9, and it will be seen that this member is yieldingly journaled in its bearings because of the ample space in the slots for the pins or pintles by which it is supported. 65 I have illustrated the rotatable member as a cylindrical, smooth, roller made of suitable material, but it will be evident that this revoluble member may be of suitable shape and conformation, or it may be a brush 70 made up of bristles, etc.

In lieu of suspending the roller on its journals in the slots of the extension, it may be yieldingly supported on the pivoted arms 10 of the tray as seen in Figs. 5 and 6, and 75 when so journaled the roller may be turned on the pivots backward to inoperative position when required.

When using the device it is preferably 80 tilted up to an angle less than 45° with the scraping edge 5 in contact with the surface to be cleaned and the roller yieldingly resting upon the surface. The handle is grasped and the tray is advanced by hand across the surface, and the yielding roller, as it 85 passes over the crumbs, is rotated and lifted until it confines a certain amount of material to be picked up, between itself and the scraping edge. Continuance of this action forces the material upon the scraping edge, 90 apparently by precluding its escape and movement away from such edge. In this manner the roller is constantly vibrating as it rotates and encounters crumbs, and for this reason it should be sufficiently light in 95 weight as not to mash the particles or crumbs too much, yet at the same time of specific gravity great enough to hold it against excessive bouncing or undue vibration. In Fig. 4 the tray is illustrated filled 100 with crumbs and the roller is in assumed normal position to prevent spilling of the accumulated particles.

Having thus fully described my invention, what I claim is:

1. In combination with a scraping pick-up blade, a gravity roller mounted on and

110

preceding said blade and adapted to yieldingly ride upon and hold immovable the material to be picked up so as to facilitate such picking up.

5. 2. In combination with a scraping pick-up blade, an idly rotatable element yieldably mounted on and in advance of said blade, said element being of a structure to ride over and hold immovable the material to be picked up.

6. 3. In combination with a scraping pick-up blade, an idly rotatable element yieldably mounted on and in advance of said blade and overlapping the forward edge

15 thereof.

4. A crumbing tray having a scraping

edge, and means immediately in advance of such edge and mounted on the tray to automatically confine and hold the material immovable for the scraping edge.

5. In combination with a scraping pick-up blade, a rotatable element yieldably supported upon and in overlapping relation to the scraping blade and adapted to assume a position to prevent return of the material 25 picked up after the blade is lifted.

In testimony whereof I affix my signature in presence of two witnesses.

GEORGE F. MAIDENS.
